METRO J. KINDRAT AND HAWRYIL ZATZERKOWNY, OF DETROIT, MICHIGAN.

NEWSPAPER-DISPENSING MACHINE.

Application filed March 7, 1925. Serial No. 18,735.

This invention relates to certain new and useful improvements in newspaper dispensing machines and has for its primary object to provide a machine that is automatic in its 5 operation, the mechanism for delivering the newspaper through a slotted opening in a side wall of the machine casing being placed in operation upon the depositing of a coin in the machine.

10 Another object of the invention is to provide an improved coin slot construction for a newspaper dispensing machine wherein the mechanism for mechanically delivering or dispensing the newspaper is placed in operation upon the depositing in the coin slot of the proper coin while a coin of improper 15 value will be returned to the prospective purchaser.

With the above general objects in view 20 and others that will appear as the nature of the invention is better understood, the same consists of the novel form, combination and arrangement of parts hereinafter more fully described, shown in the accompanying drawings and claimed.

In the drawings, wherein like reference characters designate like parts throughout the same,

Figure 1 is a front elevational view of a 30 newspaper dispensing machine constructed in accordance with the present invention,

Figure 2 is a vertical longitudinal sectional view showing the coin operated mechanism and the delivering devices for the 35 newspaper with a stack of newspapers supported within the machine,

Figure 3 is a horizontal sectional view taken on line III—III of Fig. 2 showing the 40 spring motor operating mechanism and the paper delivery arm,

Figure 4 is a fragmentary horizontal sectional view showing a part of the elevating mechanism for the paper supporting platform and the brake device associated therewith,

Figure 5 is a horizontal sectional view taken on line V—V of Fig. 2 showing the 45 spring supported platform for the newspapers,

50 Figure 6 is a detail sectional view taken on line VI—VI of Fig. 1 showing the link connections between the upper rollers for the paper supporting platform and the gear train and brake device for arresting movement of the platform when all of the papers 55 have been delivered from the machine,

Figure 7 is a fragmentary detail sectional view of the lower end of the machine with the paper supporting platform in its lowered position,

60 Figure 8 is a fragmentary sectional view showing the paper supported platform at its limit of upward movement with the sign card indicating that all papers have been delivered viewable through a transparent opening or window in the front wall of the casing,

65 Figure 9 is a fragmentary front elevational view with the sign card alined with the casing window,

70 Figure 10 is a detail sectional view showing one of the upper rollers having a sprocket chain connection with the paper supporting platform,

75 Figure 11 is a cross sectional view taken on line XI—XI of Fig. 10,

Figure 12 is a cross-sectional view taken on line XII—XII of Fig. 10,

80 Figure 13 is a fragmentary perspective view showing the coin box and the rod for opening the hinged bottom thereof,

Figure 14 is a top plan view of the coin chute,

85 Figure 15 is a longitudinal sectional view of the coin chute,

Figure 16 is a fragmentary view showing the crank connection for the rear end of each of the newspaper delivering arms, and

90 Figure 17 is a fragmentary view showing the intermediate crank connection for the newspaper delivering arms to effect elevation of the forward end of the arm during operation thereof.

The newspaper dispensing machine disclosed in this application embodies a casing 95 having front and rear walls 1 and 2, side walls 3 and 4 and top and bottom walls 5 and 6, the casing being preferably mounted upon supporting feet 7 while entrance thereto is gained through a hinged side door 8.

100 To support a stack of newspapers B within the casing as shown in Fig. 2, a spring supported platform and elevating means therefor are provided and embody a pair of tensioned rollers 9 parallel with the front and rear walls 1 and 2 adjacent the upper end of the casing while a pair of cooperating guide shafts 10 are similarly journaled adjacent the lower end of the casing as shown in Fig. 2. The rollers 9 and shafts 10 are 105 provided with sprocket wheels 11 at each end thereof and over which endless sprocket

chains 12 travel. The paper supporting platform 13 is secured at its corners as at 14 to the inner sides of the sprocket chains 12 and upon movement of the sprocket chains, 5 the platform 13 is raised and lowered.

The cushion support for the platform 13 embodies a tapering helical spring 15 having the upper convolution thereof secured to a plate 16 that is centrally anchored to the 10 lower face of the platform 13 while the lower larger convolution of the helical spring is secured to the band 17 spaced upwardly of the bottom wall 6 of the casing as shown in Fig. 2. In order to hold the platform in 15 its lowered position for the purpose of placing a stack of papers B thereon, there is provided a shaft 18 journaled adjacent the stand 17 with a hand operated crank handle 19 upon one end thereof, the drum 20 fixed 20 to said shaft intermediate the ends thereof having a cable 21 wound thereon with the free spent end secured at 22 to the plate 16 and platform 13. Upon rotating the shaft 18 in the proper direction, the cable 21 is 25 wound thereon and the platform 13 is lowered for compressing the spring 15 as shown in Fig. 7 and the platform is retained in its lowered position by the hook 23 carried by the stand 17 placed into engagement with 30 the eye 24 carried by the plate 16. With the platform so lowered, the door 8 of the casing being opened, a stack of papers is mounted upon the platform to the desired elevation.

The prime movers for the platform being 35 the rollers 9 that are rotatably tensioned with the coil spring 15 assisting in the elevation of the platform, said rollers being shown in detail in Figs. 10 to 12, each embodies a cylindrical casing rotatably supported in the side walls 3 and 4 of the machine casing with a shaft 25 journaled therein. Each end of the roller 9 has the sprocket wheel 11 fixed thereto while that end of the roller adjacent the casing wall 3 carries a 40 ratchet wheel 26 with which a spring pressed pawl 27 is associated as shown in Fig. 12. A coil spring 28 surrounds the shaft 25, one end thereof being secured as at 29 to the shaft while the other end is anchored as at 45 30 to the casing of the roller 9. The two upper rollers 9 having the sprocket chains 12 passing over the sprocket wheels 11 thereof and with the platform 13 secured to the inner sides of the sprocket chains, downward 50 movement of the platform causing rotation of the rollers 9 will place the springs 28 under tension, the pawl and ratch mechanism preventing rotation of the shaft 25 during lowering movement of the platform. The 55 end of the shaft adjacent the side wall 3 of the casing is provided with a key receiving end 31 to permit rotation of the shaft for placing additional tension upon the spring 28 should it be so desired.

60 The platform 13 travels upwardly in a

step by step movement during the dispensing of newspapers through the opening 32 in the front wall of the casing as shown in Fig. 2 and when the last paper has been dispensed, the sign plate 33 carried by the inner sides of the sprocket chains 12 adjacent the front wall 1 of the casing and having the legend 34, "Empty" thereon will be positioned in alignment with the window 35 in the front wall 1 of the casing to indicate 70 that all of the newspapers have been sold.

A housing 36 is carried by the side wall 4 of the casing adjacent the rollers 9 which encloses mechanism for controlling the operation of the rollers 11 in elevating the platform. As shown in Fig. 10, the roller 9 journaled in the side wall 9 of the casing and extending into the housing 36 has a gear wheel 37 fixed thereto that has an eccentric rod connection 38 with the lever 39 projecting from the corresponding end of the forwardly positioned roller 9, this latter construction being more clearly shown in Fig. 6. A train of gearing including a pinion 40 that meshes with the gear 37 is fixed to a 90 shaft 41 that carries a gear 42 meshing with a pinion 43 upon the shaft 44 which in turn carries a gear 45 meshing with a pinion 46 upon the shaft 47, the several shafts 41, 44 and 47 being journaled in the side walls 4 of the casing and the outer side wall of the housing 36. A brake drum 48 is keyed to the shaft 47 and is adapted to be engaged by a brake shoe 49 of arcuate formation as 95 shown in Fig. 6 which is carried by the lever 50 pivotally supported as at 51 with an overbalanced free end having a roller 52 secured thereon. The lever 50 extending through the side wall 4 of the casing as the roller supporting end thereof disposed above the stack of papers P with the upper paper of the stack adapted to engage the roller 52 to elevate the same and cause the brake shoe 39 to be lowered into engagement with the 100 brake drum 48 for arresting rotary movement of the platform elevating rollers 9. When the upper paper of the stack P is delivered through the opening 32 by mechanism to be now described, the weighted end of the lever 50 including the roller 52 will 105 be lowered with the brake shoe 49 disengaged from the brake drum 48 to permit operation of the rollers 9 and the elevation of the platform 13 to cause the following 110 paper of the stack to engage the roller 52, elevate the same with the lever 50 and again move the brake shoe 49 into engagement with the brake drum 48 to hold the rollers 9 against movement. By the provision of the 115 link rod and lever connection between the two elevating rollers 9, movement of both rollers is arrested when the brake shoes moves into engagement with the brake drum.

120 The mechanism for delivering the news- 130 papers from the stack 8 to the exit opening

32 in the front wall 1 of the casing is shown more clearly in Figs. 2 and 3 and includes a spring motor having a shaft 53 provided with a key end 54, the key end of the shaft 5 being journaled in the casing wall while the opposite end 55 thereof is journaled in the elongated bearing 56 that extends to the opposite wall 4 of the casing as shown in Fig. 3. A coil spring 57 surrounds the shaft 53, the spring being of the band type with the inner end thereof anchored to the shaft while the outer end of the spring is anchored to the cylindrical casing. It will therefore be seen that upon rotating the shaft 53 through the medium of the key end 54 the band spring 57 is placed under tension and is so retained by the spring pressed pawl 59 engaging the ratchet wheel 60, shown more clearly by dotted lines in Fig. 2, it being noted that the ratchet wheel 60 is fixed to the shaft 53. A gear wheel 61 fixed to an end of the spring casing 58 meshes with the pinion 62 upon the shaft 63 located beneath the motor shaft 53 and the shaft 63 has a gear 64 thereon that meshes with the pinion 65 and 66, respectively mounted upon the crank shaft 67 and 68 journaled in the side walls 3 and 4 of the casing. It will therefore be seen that when the spring motor is in operation, the crank shafts 67 and 68 are rotated.

Crank portions 69 and 70 are carried by the crank shaft 67 and 68 respectively, each crank shaft being preferably provided with four crank portions and with which newspaper delivery arms 71 are associated as shown in Figs. 2, 16 and 17, each of the arms 71 having an offset shoulder portion 72 and upwardly arched from the shouldered portion to the forward end thereof as at 73 with a slotted portion 74 in the arched portion of each arm with which the crank portions 70 of the shaft 68 are associated, a roller bearing 75 on each crank portion reducing friction between the parts as shown in Fig. 17. The arms 71 are supported by the crank portions of the shafts 67 and 68 and the forward end of each arm carries a finger 76 hinged to the arm as at 77 and spring pressed as at 78 for normally influencing the pin 79 carried by the finger into piercing engagement with the upper newspaper in the stack P as shown in Fig. 2. When the spring motor is in operation, the crank shaft 67 operates to move the arms 71 in a forward direction toward the paper exit opening 32 while the crank shaft 68 associated with the slotted arched portions of said arms elevates the forward ends of the arms during rotation thereof for disengaging the fingers 76 from the upper paper in the stack.

Devices are provided for holding the spring motor against operation and coin operated mechanism is associated with said device, the crank shaft 68 having a pinion 80 fixed thereto intermediate its ends that

meshes with the worm 88^a upon the shaft 88 that is journaled in frame 89. The pinion 81 fixed to the shaft 82 as shown in Figs. 2 and 3 meshes with worm 88^a, this mechanism being similar to the disk rotating mechanism of a phonograph. A disk wheel 83 fixed to the shaft 82 has a cam formation on its peripheral edge with a stop shoulder 84 that is engaged by the finger 85 for holding the disk wheel 83 against rotation and also acting as a stop for the driving devices and spring motor associated with the paper delivering arms 71. To control the speed of operation of the spring motor and its associated mechanism, a horizontal gear 86 fixed to the upper end of the shaft 88 meshes with a pinion 87, the supporting shaft of which carries a speed governor 90. This driving mechanism reduces the strain on the finger 85 and assures a relatively slow and even movement of the parts.

The fingers 85 forms a part of the coin operated mechanism and is carried by a rack segment 91 journaled in the casing which meshes with the rack segment 92 formed at one side of the larger rack segment 93 journaled in alignment with the segment 91 while the rack segment 93 meshes with the rack segment 94 that carries the arm 95 shown in detail in Fig. 13. The rack segment 94 is pivotally supported as at 96 and has a coin cup 97 fixed to the outer end thereof while a link 98 connects the arm 95 to the coin gage bar 99 that is pivotally supported as at 100 with a block 101 slidable thereon for determining the denomination or weight of the coin for tilting the coin box 97. A bottom 102 is hinged to the coin box at 103 and is normally retained in its closed position by the spring 104 positioned between the bottom 102 and the arms 95. The bottom 102 of the coin box is opened by the lever 105 pivoted within the casing as at 106, one end of the lever 105 having a link connection 107 with the crank 108 carried by the shaft 82 while the other end of the lever 105 carries a depending rod 109 entering the open upper end of the coin box 97 to engage the bottom 102 and open the same against the tension of the springs 104 in a manner to be presently described.

The coin chute is shown in detail in Figs. 14 and 15 and embodies a frame that is rectangular in cross-section and of elongated formation with a bottom wall 110, a top wall 111 and side walls 112 and 113, the coin chute being open at opposite ends as illustrated. A flexible arm 114 is fixed intermediate its ends as at 115 to the side wall 112 of the coin chute and screws 116 threaded thru the side wall 112 of the coin chute engage the flexible strip 114 adjacent each end thereof for varying the distances between the upper and lower ends of the flexible strip and the opposite side wall 113 of the coin chute.

Graduations 117 are formed on the upper face of the bottom wall 110 of the coin chute adjacent the ends of the flexible strip to indicate the distance between the opposite ends of the flexible strip and the side wall 113 corresponding, for instance, to the diameter of a penny, five cent piece and a dime. A semi-circular opening 118 is formed in the bottom wall 110 of the coin chute adjacent the lower end of the flexible strip 114 and the bottom wall of the coin chute below the opening 118 is depressed as at 119 and has a pin 120 projecting perpendicularly therefrom for engaging one side edge of the coin of proper denomination to suddenly stop the passage of the coin through the chute and cause a backward throw thereof through the opening 118 into the coin box 97. Should the opposite ends of the flexible strip be set for the insertion of a nickel in the coin chute, the entrance of a penny or dime therein permit the same to travel through the coin chute, pass over the opening 118 and escape, the pin 120 to be directed into the chute 121, shown in Fig. 2 and deposited in the cup 122 for return to the prospective purchaser.

In the use of the newspaper dispensing machine disclosed in this application, and assuming that the platform 13 for supporting the stack of papers P is at its limit of upward movement, the door 8 is opened and by rotating the shaft 18 through the medium of the crank handle 19, the cable or cord 21 attached at its upper end to the platform 33 is wound upon the drum 20 with the platform lowered against the tension of the spring 15 and compressing the latter as shown in Fig. 7. During the lowering movement of the platform, the rollers 9 are revolved by the chain and sprocket mechanism connected to the platform and the spring 28 of each of the upper rollers is placed under tension. Additional tension may be placed upon the springs 28 by applying a wrench to the key end 31 of the shaft 25 of the roller. When the platform is in its lowered position, the same is momentarily so retained by the hook and eye 23-24. With the papers stacked upon the platform 13, the upper paper engages the weighted roller 52 to elevate the same and lower the brake shoe 49 into engagement with the brake drum or wheel 48, thereby holding the gear and link connected rollers 9 against movement.

When a coin of the proper denomination is inserted into the coin chute, the same will strike the lower end of the flexible strip 114 and the pin 120 and be thrown backwardly through the opening 118 into the coin cup 97 and the weight of the coin in the cup will cause a lowering movement thereof and relative movement of the meshing rack segments 91 to 94 shown in Fig. 2 to disengage the finger 85 from the cam lug 84 upon the

periphery of the disk wheel 83, it being understood that during this movement the bottom 102 of the coin box remains in its closed position. With the finger 85 disengaged from the cam lug upon the disk wheel 83, the spring motor associated with the shaft 53 shown in Figs. 2 and 3 operates the chain of gearing, crank shafts 67 and 68 and shaft 82 that has the crank connection 108 with the lever 105, operation of the lever 105 causing the rod 109 to be moved in a downward direction to open the bottom 102 of the coin box to permit the discharge of coin into a suitable receptacle. The speed of operation of the mechanism is controlled by the governor 90 and worm 88^a interposed between the pinions 80 and 81.

When the crank shafts 67 and 68 are rotated, the paper delivering arms 71 are moved forwardly and the pin 79 upon the finger 76 engaging the upper paper of the pile as shown in Fig. 2 projects the forward edge of the paper through the delivery opening 32 in the front wall of the casing. Rotation of the crank shaft 67 causes the crank portion 69 thereof to move the arm 71 in a forward direction while the crank shaft 68 having the crank portion 70 associated with the slot 74 in the upwardly arched portion 73 of said arm causes an elevation at the forward end of the arm to disengage the finger 76 from the paper. The paper being partially projected through the opening 32, the same is then removed by the purchaser and as the upper paper of the pile is removed from engagement with the weighted roller 52, the latter is lowered to elevate the brake shoe 49 from the brake drum 48 to permit operation of the gearing mechanism shown in Fig. 4 together with the elevating rollers 9 for the platform 13, the platform then being elevated until the uppermost paper in the stack engages the roller 52 to elevate the same and again apply the brake shoe to the brake drum. When the last paper has been dispensed from the machine, the fine plate 33 is disposed in line with the window 35 to indicate that the machine is empty.

While there is herein shown and described the preferred embodiment of the present invention, it is nevertheless to be understood that minor changes may be made therein without departing from the spirit and scope of the invention as claimed.

What is claimed is:—

1. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, and a brake shoe for the drum operated by the

stack of papers to hold the spring rollers against movement.

2. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, and an overbalanced lever carried by the brake shoe in the upward path of movement of the stack of papers.

3. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, a coil spring interposed between the platform and bottom of the casing to assist the spring rollers in the elevation of the platform, a shaft and drum adjacent the bottom of the casing, a cable wound on the drum attached to the platform whereby the latter may be manually lowered for placing a stack of papers thereon, and means for holding the platform in its lowered position.

4. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, a shaft and drum adjacent the bottom of the casing, a cable wound on the drum attached to the platform whereby the latter may be manually lowered for placing a stack of papers thereon, and means for holding the platform in its lowered position.

5. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, a coil spring interposed between the platform and bottom of the casing to assist the spring rollers in the elevation of the platform, a shaft and drum

adjacent the bottom of the casing, a cable wound on the drum attached to the platform whereby the latter may be manually lowered for placing a stack of papers thereon and means for holding the platform in its lowered position.

6. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, a coil spring interposed between the platform and bottom of the casing to assist the spring rollers in the elevation of the platform, a shaft and drum adjacent the bottom of the casing, a cable wound on the drum attached to the platform whereby the latter may be manually lowered for placing a stack of papers thereon, and means for holding the platform in its lowered position.

7. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, a plurality of arms having tensioned fingers engaging the upper paper of the stack for moving the same through the delivery opening, and operating means for said arms.

8. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, a plurality of arms movably mounted above the stack of papers, spring fingers pivoted to the arms and engaging the upper paper of the stack for moving the same through the delivery opening, and operating means for said arms.

9. In a newspaper dispensing machine, a casing having a delivery opening therein, a vertically moving paper supporting plat-

form in the casing, means for elevating the platform including endless sprocket chains, spring rollers for the upper ends of the chains, connections between the rollers including a gear train and brake drum, a brake shoe for the drum operated by the stack of papers to hold the spring rollers against movement, a shaft and drum adjacent the bottom of the casing, a cable wound on the drum attached to the platform whereby the latter may be manually lowered for placing a stack of papers thereon, means for holding the platform in its lowered position, a plurality of arms engaging the upper paper of the stack for moving the same through the delivery opening, and operating means for said arms.

10. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, a shaft and drum adjacent the bottom of the casing, a cable wound on the drum attached to the platform whereby the latter may be manually lowered for placing a stack of papers thereon, means for holding the platform in its lowered position, a plurality of arms engaging the upper paper of the stack for moving the same through the delivery opening, and operating means for said arms.

40. 11. In a newspaper dispensing machine, a casing having a delivery opening therein, a vertically moving paper supporting platform in the casing, means for elevating the platform including endless sprocket chains, spring rollers for the upper ends of the chain, connections between the rollers including a gear train and brake drum, a brake shoe for the drum operated by the stack of papers to hold the spring rollers against movement, a coil spring interposed between the platform and bottom of the casing to assist the spring rollers in the elevation of the platform, a shaft and drum adjacent the bottom of the casing, a cable wound on the drum attached to the platform whereby the latter may be manually lowered for placing a stack of papers thereon, means for holding the platform in its lowered position, a plurality of arms engaging the upper paper of the stack for moving the same through the delivery opening, and operating means for said arms.

50. 12. In a newspaper dispensing machine, a casing having a delivery opening therein, a vertically moving paper supporting plat-

form in the casing, means for elevating the platform including endless sprocket chains, spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, a coil spring interposed between the platform and bottom of the casing to assist the spring rollers in the elevation of the platform, a shaft and drum adjacent the bottom of the casing, a cable wound on the drum attached to the platform whereby the latter may be manually lowered for placing a stack of papers thereon, means for holding the platform in its lowered position, a plurality of arms engaging the upper paper of the stack for moving the same through the delivery opening, and operating means for said arms.

55. 13. In a newspaper dispensing machine, a casing having a delivery opening in the front wall thereof, a vertically moving paper supporting platform in the casing, means for elevating the platform, said elevating means being held inoperative by the stack of papers on the platform, a plurality of mechanically operated arms engaging the upper paper of the stack for moving the same through the delivery opening, and means operating to advance the arms and elevate the forward ends thereof to free the same from the paper when the paper has been partially projected through the casing opening.

60. 14. In a newspaper dispensing machine, a casing having a delivery opening in the front wall thereof, a vertically moving paper supporting platform in the casing, means for elevating the platform, said elevating means being held inoperative by the stack of papers on the platform, a window in the casing, a sign plate carried by the platform to be moved in line with the window to indicate when the machine is empty, a plurality of mechanically operated arms movably mounted above the stack of papers, spring fingers pivoted to the arms and engaging the upper paper of the stack for moving the same through the delivery opening, and means operating to advance the arms and elevate the forward ends thereof to free the same from the paper when the paper has been partially projected through the casing opening.

65. 15. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake

shoe for the drum operated by the stack of papers to hold the spring rollers against movement, a plurality of mechanically operated arms engaging the upper paper of the stack for moving the same through the delivery opening, and means operating to advance the arms and elevate the forward ends thereof to free the same from the paper when the paper has been partially projected through the casing opening.

16. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, a plurality of mechanically operated arms engaging the upper paper of the stack for moving the same through the delivery opening, and means operating to advance the arms and elevate the forward ends thereof to free the same from the paper when the paper has been partially projected through the casing opening.

17. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, a coil spring interposed between the platform and bottom of the casing to assist the spring rollers in the elevation of the platform, manually operable means for retracting the spring and lowering the platform, a plurality of mechanically operated arms engaging the upper paper of the stack for moving the same through the delivery opening, and means operating to advance the arms and elevate the forward ends thereof to free the same from the paper when the paper has been partially projected through the casing opening.

18. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against

movement, an over-balanced lever carried by the brake shoe in the upward path of movement of the stack of papers, a coil spring interposed between the platform and bottom of the casing to assist the spring rollers in the elevation of the platform, a card and pulley device for lowering the platform against spring tension, a plurality of mechanically operated arms engaging the upper paper of the stack for moving the same through the delivery opening, and means operating to advance the arms and elevate the forward ends thereof to free the same from the paper when the paper has been partially projected through the casing opening.

19. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, a shaft and drum adjacent the bottom of the casing, a cable wound on the drum attached to the platform whereby the latter may be manually lowered for placing a stack of papers thereon, means for holding the platform in its lowered position, a plurality of mechanically operated arms engaging the upper paper of the stack for moving the same through the delivery opening, and means operating to advance the arms and elevate the forward ends thereof to free the same from the paper when the paper has been partially projected through the casing opening.

20. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, a shaft and drum adjacent the bottom of the casing, a cable wound on the drum attached to the platform whereby the latter may be manually lowered for placing a stack of papers thereon, means for holding the platform in its lowered position, a plurality of mechanically operated arms engaging the upper paper of the stack for moving the same through the delivery opening and means operating to advance the arms and elevate the forward ends thereof to free

the same from the paper when the paper has been partially projected through the casing opening.

21. In a newspaper dispensing machine, a casing having a delivery opening therein, a vertically moving paper supporting platform in the casing, means for elevating the platform including endless sprocket chains, spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, a coil spring interposed between the platform and bottom of the casing to assist the spring rollers in the elevation of the platform, a shaft and drum adjacent the bottom of the casing, a cable wound on the drum attached to the platform whereby the latter may be manually lowered for placing a stack of papers thereon, means for holding the platform in its lowered position, a plurality of mechanically operated arms engaging the upper paper of the stack for moving the same through the delivery opening, and means operating to advance the arms and elevate the forward ends thereof to free the same from the paper when the paper has been partially projected through the casing opening.

22. In a newspaper dispensing machine, a casing having a delivery opening therein,

a vertically moving paper supporting platform in the casing, means for elevating the platform including endless sprocket chains, 35 spring rollers for the upper ends of the chains, connections between the rollers including a gear train and brake drum, a brake shoe for the drum operated by the stack of papers to hold the spring rollers against movement, an overbalanced lever carried by the brake shoe in the upward path of movement of the stack of papers, 40 a coil spring interposed between the platform and bottom of the casing to assist the spring rollers in the elevation of the platform, a shaft and drum adjacent the bottom of the casing, a cable wound on the drum attached to the platform whereby the latter may be manually lowered for placing a stack 45 of papers thereon, means for holding the platform in its lowered position, a plurality of mechanically operated arms engaging the upper paper of the stack for moving the same through the delivery opening, and means operating to advance the arms and elevate the forward ends thereof to free the same from the paper when the paper has been partially projected through the casing 50 opening.

In testimony whereof we affix our signatures.
